UNITED STATES PATENT OFFICE.

JUAN FORSECK, OF SAN LUIS POTOSÍ, MEXICO.

HACKLING-MACHINE.

1,046,168.

Specification of Letters Patent.

Patented Dec. 3, 1912.

Application filed July 3, 1911. Serial No. 636,653.

To all whom it may concern:

Be it known that I, JUAN FORSECK, a citizen of the United States of America, residing at San Luis Potosí, State of San Luis Potosí, Mexico, have invented certain new and useful Improvements in Hackling-Machines, of which the following is a specification.

My invention relates to improvements in machines for tearing up the leaves of fibrous plants such as the maguey plant, hitherto refractory to shredding, and also the lechuguilla and for removing all the bagasse or fleshy parts from the fibers at the same time and to which action the leaves are gradually subjected in such a manner that the hackling takes place endwise and approaches the middle of the leaves and in a second stage of the operation the same action is effected from the end of the other half of the leaves and clearing beyond the middle of the leaves in order not to leave any part of the entire length of the leaves without treatment.

The object of such gradual treatment is to remove the bagasse or fleshy parts in small portions by the hackling drums and by stripping the fibers from the extremities of the leaves toward the middle of the leaves so that choking or accumulation of the separated bagasse or fleshy parts is avoided and which otherwise, as deposits, adhering to the fibers, would present a serious obstacle to an advantageous working on plants with soft and fine fibers.

My machine furthermore provides an effective means for retaining the cleared fibers against the pull of the hackling drums.

In order that the invention may be more fully understood I will proceed to describe it with reference to the accompanying drawings in which:

Figure 1 is a top view of my improved hackling machine; the conveyer chains being omitted. Fig. 2 is a side elevation of the same; the conveyer chains being indicated in broken lines. Fig. 3 is a front end view thereof; the gear wheels and conveyer chains being omitted. Fig. 4 is an elevation of the double standard for the front end of the

drum journals and the transmission gear, 50 Fig. 5 is a detail side view of the rear wheel for the upper conveyer chain showing the upper supporting beams therefor in section. Fig. 6 is a transverse section of a conveyer wheel rim provided with a rubber tire. Fig. 55 7 is a transverse section of a conveyer wheel rim having radial retaining pins on the inner flange of its rim.

This machine will preferably be mounted on wheels, not shown, in order to readily 60 transport it in mountainous districts. The framework is constructed with longitudinal lower U-beams 1, longitudinal intermediate U-beams 2, and longitudinal upper U-beams 3, and transverse arched beams 4, one at each 65 end.

A is the first hackling drum, of conical shape, located near to one side of the framework, with its smaller end directed toward the feed end of the machine. This first 70 hackling drum is fixed to a driving shaft 5 journaled in the single standards 6 and the double standards 6^a which rest upon the lower beams 1. The driving shaft 5 is provided at its inner end with a worm 7 and at 75 its outer end it carries the gear wheel 8, and a driving pulley 9, from which the various parts of the machine receive movement. Retired or isolated from the first hackling drum A, is a second hackling drum B, also 80 of conical shape, located near to the other side of the framework with its smaller end also directed toward the feed end of the machine. This second hackling drum B is fixed to a driven shaft 10, journaled in two 85 standards 11, and the double standard 6^a, all of which rest on the lower beams 1. To the front end of this driven shaft 10, is secured the gear wheel 12, which is meshed by the gear wheel 8, on the driving shaft 5, 90 and rotates the second hackling drum B in a direction contrary to the movement imparted to the first hackling drum A.

The conveyance of the leaves is effected transversely in front of the first hackling 95 drum A, and the means employed consists of a front conveyer wheel 13, a lower and larger intermediate conveyer wheel 14, and

a rear conveyer wheel 15. The front conveyer wheel 13 is mounted in short arms 17 pivoted to the outer ends of the upper beams 3, and yieldingly pressed downward by leaf 5 or plate springs 18 extending thereover. The intermediate conveyer wheel 14, of which a cross section of its rim is shown in Fig. 7, has a number of radial retaining pins 19 on the inner flange of its rim which faces 10 the first hackling drum A, whereby even under a great lateral pull the upper conveyer chain 16 and the lower conveyer chain 20, may be kept within the channel of the rim. The rear conveyer wheel 15, is mounted 15 on an axial pin 15^a supported in a turn on a sleeve 15^c having lugs 15^b and 15^d respectively secured by bolts 15^e to and between the upper beams 3.

Coöperating with the upper conveyer 20 chain 16 is the lower conveyer chain 20, running over a lower front conveyer wheel 21, supported on a pedestal 22, and also over a small conveyer pulley 23 adjacent to the intermediate conveyer wheel 14 and then below the latter over another conveyer wheel 24 secured to a conveyer drum 25 in rear of the intermediate conveyer wheel 14, see Fig. 1, and finally under an intermediate conveyer idler wheel 26 at the base of the 25 framework.

The carrying of the half treated leaves in front of the second hackling drum B is accomplished by a single conveyer chain 27 traveling over a conveyer wheel 28 and also 30 under a larger conveyer wheel 30 also attached to the conveyer drum 25 and then over a conveyer wheel 29, while the larger intermediate conveyer wheel 30 having a rubber tire 31 (see Fig. 6) offers a very 35 effective hold on the fibers confined between the conveyer chain 27 and the tire 31. The conveyer wheel 29 is supported in a sliding block 32, which plays within a slot 33, of a standard 34, and is forced upward by a 40 spring, not shown, surrounding the extremity of a screw bar 35, provided with a nut 36 for adjusting the tension.

In Fig. 1 the conveyer wheel 29 is shown as having attached thereto a drum 37 on the 45 top of which a rubber belt 38 is moved by friction; this rubber belt 38 running over the belt pulleys 39 and 40, and drawing the cleared fibers from the intermediate conveyer wheel 30, above the conveyer wheel 29 and the drum 37 from where the fibers are 50 discharged. The shaft 41 upon which the conveyer wheel 24, the conveyer drum 25, and the conveyer wheel 28, are secured has also attached to it at its outer end the worm 55 wheel 42.

The conveyer drum 25 is provided for the purpose of supporting the cleared parts of the leaves and prevents such parts from falling 60 between the two parallel running sets of

conveyer chains and also for lifting the 65 cleared parts of the leaves which after being cleared are slack, and so that the cleared parts may be placed on top of the conveyer chain 27 where it turns around the conveyer wheel 28.

Both of the hackling drums are provided 70 with encircling rows of teeth 43 arranged with decreasing spaces between them toward the base of the cone.

It will now be understood that in opera- 75 tion the different parts of the machine being moved in the direction indicated by the arrows, the fibrous leaves may be inserted between the two conveyer chains 16 and 20 in such a manner that the open ends of the 80 leaves, which result from being cut off of the plant, will project against the first hackling drum A, and due to the semi-circular course, into which the intermediate conveyer wheel 14 carries the two conveyer 85 chains 16 and 20 in front of the first hackling drum A, and also in view of the conical shape of the drum, the hackling commences at the extreme end of the leaves, and as these advance toward the larger periphery of the 90 drum, a longer portion of the leaves will come within the action of the teeth, in fact almost up to that part of the leaves which is embraced by the two conveyer chains 16 and 20. By the further traveling of these 95 conveyer chains the now hackled part of the leaves, which are still integral with the other part, which is not yet treated, is drawn over the conveyer drum 25, and immediately taken hold of by the conveyer chain 27, 100 which, by the coöperation of the conveyer wheel 30, advances the leaves in front of the second hackling drum B, and, by operations similar to those of the first hackling drum A, concludes the hackling of the leaves. At this 105 stage the rubber belt 38, which is in frictional connection with the conveyer drum 37, discharges the fibers.

Having thus described my invention the following is what I claim as new therein 110 and desire to secure by Letters Patent:

1. A hackling machine comprising a shaft, a conical drum mounted on the shaft with its smaller end directed toward the feed end of the machine; the drum being provided 115 with encircling rows of teeth; the rows of teeth being decreased in distance apart from the smaller to the larger end of the drum, means for conveying the leaves in front of the working face of the drum and means for 120 rotating the drum so as to cause the working face thereof to move upwardly.

2. A hackling machine for fibrous plants comprising two parallel shafts, conical drums mounted one on each shaft and one 125 in advance of the other, each conical drum being provided with encircling rows of teeth; the rows of teeth on each drum being

decreased in distance apart from the smaller to the larger end of the drum and means for conveying the leaves in a semi-circular path in front of the working face of each of the drums and means for rotating the drums so as to cause the working faces thereof to move upwardly.

In testimony whereof I have affixed my signature in presence of two witnesses.

JUAN FORSECK.
